UNITED STATES PATENT OFFICE.

JOHN G. NICHOL AND CARL H. CARLSON, OF IRON MOUNTAIN, MICHIGAN.

STOVE-HOOD,

No. 825,238.

Specification of Letters Patent.

Patented July 8, 1906.

Application filed July 12, 1905. Serial No. 269,393.

To all whom it may concern:

Be it known that we, JOHN G. NICHOL and CARL H. CARLSON, citizens of the United States, and residents of Iron Mountain, in the county of Dickinson and State of Michigan, have invented a new and Improved Stove-Hood, of which the following is a specification.

Our invention relates to means for arresting steam, gases, and fumes arising from cooking and other stoves and deflect same through a suitable opening into the stove-uptake to be carried away with the smoke and combustion-gases from the stove.

The object had in view is to provide novel, inexpensive, and simple means for accomplishing the purpose stated, and to that end we have devised the peculiar stove-hood shown by the accompanying drawings and hereinafter fully described, the novel features being pointed out in the claims.

In the drawings, Figure 1 is a perspective view, partly broken away, in illustration of our invention. Fig. 2 is a top plan view, partly broken away. Fig. 3 is a transverse sectional view with the slide shown drawn out.

In carrying out our invention we employ any suitable canopy A, which may be constructed with a top portion B, sides C, and a rear wall D. In fashioning the canopy A provision is made for extension of the stove-uptake E up through the top portion B of the hood, as shown in Fig. 3. Suitably below the top portion B we arrange and support a partition-plate F, leaving between it and the top portion B an elongated pocket G. The pocket is made communicating through an opening H with the stove-uptake E, and walls I may be arranged in the pocket G, with the same converging inwardly to the opening H in the uptake E, substantially as indicated by dotted line in Fig. 2. In the pocket G we arrange a slide J, preferably constructed with downwardly-disposed ends J' J' and a similarly-disposed front edge J². The downwardly-disposed front edge of the slide J is designed to serve as a closure for the front opening leading into the pocket when the slide is shoved into the pocket to its inmost adjustment.

K denotes a plate or door made conforming to the outer curve of the stove-uptake E and adapted for closing the opening H therein. The door has pivotal support on the bent end I of a bar M, which latter is fixedly

secured to the under side of the slide J by rivets N or other approved means. The slide J is provided with a depending pin or shoulder O for the purpose appearing further on.

In the pocket G we arrange a shoulder P, fixedly secured by rivets F' or other means to the upper side of the partition F. The shoulder P is located to one side of the door-support I M, adapted for contact with an incline on the door, substantially as the device Q.

R denotes a pin arranged projecting into the pocket G and rendered movable into and out of obstructing contact with the shoulder O on the under side of the slide J.

The construction of our invention will be understood from the above description and the several figures of the drawings.

In the use of our invention should there be objectionable fumes or steam arising from the stove the same may be prevented from passing out into the room by simply drawing out the slide J to position shown in Fig. 3. When the slide J is drawn out, as above described, the pin R should be adjusted in line with the shoulder O on the slide, and thus serve to limit the slide's outward movement. Obviously when the pin R is moved out of line with the shoulder O the slide may be pulled out of the pocket G. Now obviously upon drawing out the slide the incline device Q on the door K will engage the fixed shoulder P, thereby swinging the door to the dotted position, whereby as much as possible removing obstruction to direct entrance of the objectionable fumes through the opening in the uptake for free passage-way thereof into the chimney to be carried away therethrough with the smoke and products of combustion from the stove. When starting a fire in the stove, obviously the slide should be shoved into the pocket to position with the door K, closing the opening H in the uptake E, and with its outer turned-down edge J² closing the front entrance into the pocket G.

While our invention is shown and described in its preferred form and adaptation, it is obvious that the same may be variously modified without departing from the scope and spirit of the invention.

Having thus described our invention, what we claim as new, and desire to secure by Letters Patent, is—

1. The combination with the uptake of a

- stove, of a hood, consisting of a canopy, having a suitable pocket, and with the stove-uptake extended upwardly through the hood, the uptake being provided with an opening, 5 affording free passage-way leading from the pocket into the uptake, a slide in the pocket, and a door carried by the slide, the door being adapted for closure of the opening in the uptake, substantially as described.
- 10 2. The combination with the uptake of a stove, of a hood, consisting of a canopy, having a suitable pocket, and with the stove-uptake extended upwardly through the hood, the uptake being provided with an 15 opening, affording free passage-way leading from the pocket into the uptake, a slide in the pocket, a door carried by the slide, the door being adapted for closure of the opening in the uptake, a shoulder on the slide, 20 and a pin on the hood, the latter being provided with adjustment, whereby to limit movement of the slide, substantially as described.
- 25 3. The combination with the uptake of a stove, of a hood, consisting of a canopy, having a suitable pocket, and with the stove-

uptake extended upwardly through the hood, the uptake being provided with an opening, affording free passage-way, leading from the pocket into the uptake, a slide in 30 the pocket having its front edge fashioned for closure of pocket's inlet-opening, a door having pivotal support on the slide, and adapted for closure of said opening in the uptake, a shoulder on the slide, and a pin on the hood, the latter being provided with adjustment, whereby to limit movement of the slide, substantially as described.

4. The combination with the uptake of a stove, having a suitable opening in its side 40 wall, of a hood, a slide having support on the hood, a door having pivotal support on the slide, a shoulder arranged adapted for effecting movement of the door, a shoulder on the slide, and a pin on the hood, with the latter 45 serving to limit movement of the slide, substantially as described.
